By Thomas L. Ryan

ATTORNEY

UNITED STATES PATENT OFFICE.

JAMES R. COMPTON, OF KEWANNA, INDIANA.

APPARATUS FOR CONSTRUCTING WALLS OF CONCRETE.

Application filed March 24, 1925. Serial No. 17,996.

To all whom it may concern:

Be it known that I, JAMES R. COMPTON, a citizen of the United States, residing at Kewanna, in the county of Fulton and State of Indiana, have invented new and useful Improvements in Apparatus for Constructing Walls of Concrete, and of which said invention the following is a specification.

10 This invention relates to improvements in apparatus to facilitate the forming of concrete structures.

The object of my invention is to provide mold plates and connector parts therefor, 15 so constructed and combined and capable of being so manipulated, that a concrete wall structure may be formed accurately and expeditiously by the exercise of only ordinary skill.

20 My invention contemplates the combination of a pair of mold plates, tie bolts and connections to retain the plates spaced apart, and which tie bolts are capable of being easily removed from the concrete 25 after the plates are removed, cross pins adapted to be disposed in the holes formed by the removing of the said tie bolts, longitudinal track bars adapted to rest on the projecting portions of the cross pins and to 30 support a mold plate at each side of the concrete structure, latches carried by the track bar to hold it on the cross pins and clamp means on the track bars to press 35 against the mold plates.

35 The preferred form of the several parts of my improved apparatus, and the combination and arrangement thereof, for carrying my invention into effect, are shown in the drawings, in which suitable reference 40 characters are used.

Figure 1 is a side view showing the corner mold-plates set up in readiness to receive the plastic material.

Figure 2 is a top plan view of Figure 1. 45 Figure 3 shows the base piece of the corner structure after having been molded in the mold plates as seen in Figure 1; the said mold-plates having been bolted to position on the said base piece and in readiness to receive the plastic material.

Figure 4 shows the concrete corner structure after having been developed to higher level in the mold-plates at the position shown in Figure 3; the said mold-plates 50 being bolted to a further raised position

and in readiness to again receive the plastic material.

Figure 5 shows the concrete corner structure developed to the height shown in Figure 3; the mold plates having been removed, 60 and the tie-bolts having been removed and whereby the holes, spaced as shown, are provided.

Figure 6 shows the wall mold-plates at set position to receive the plastic material. 65

Figure 7 is a plan view of Figure 6.

Figure 8 is a view of Figure 6, as seen in direction of the arrow 8.

Figure 9 shows the first section of the wall bottom-course completed, and the wall 70 mold-plates set at advanced position for another filling of the plastic material.

Figure 10 shows the bottom wall-course completed to the extent for which the molds were set, (as shown in Figure 9), the track 75 bars having been placed in position and the mold-plates being set thereon in readiness for forming the first section of the second wall-course.

Figure 11 is a view of Figure 10, in direction of arrow 11. 80

Figure 12 shows the completion of the wall according to the setting of the mold-plates in the preceding view, the said mold-plates in the present view having been advanced on the track bars and set for another forming of the plastic material. 85

Figure 13 is an enlarged cross section view taken on the line 13-13 in Figure 12.

Figure 14 is an enlarged cross section view taken on the line 14-14 in Figure 12. 90

Figure 15 is a detail view of a section of the track bar and its connections.

Figure 16 is a detail view of the cross pin latch dog. 95

Figure 17 is a detail view of the check lugs.

Figure 18 is a cross section view on line 18-18 in Figure 15.

Figure 19 is a detail view of the tie-bolt 100 latch.

For constructing the concrete corner structure I provide an outer angle mold-plate of sheet metal and which in the present case is shown having a length of thirty 105 two inches. The body portions A and A¹ are bent at a right angle to each other and the sides B and B¹ are each inturned at a right angle, as shown in the plan view Figure 2, the transverse dimensions of the said 110

side portion being that desired for the thickness of the wall.

An inner-angle mold-plate having its body portion C and C¹ bent at a right angle to each other, is provided with lower, intermediate and upper holes designated as D, E, and F respectively near the edge of each body portion, and spaced as shown in Figure 1, and which said holes register with holes similarly spaced in the outer-angle mold-plate. Tie bolts H constructed as shown in Figure 13 serve to hold these said mold-plates at correct relative spaced position, and perform a further function of providing suitable bores in the concrete for the reception of the cross pins hereinafter to be referred to.

For wall construction of the thickness herein illustrated, namely, eight inches, each of the said bolts H is seven eighths of an inch in diameter, and eight inches, shoulder to shoulder; the grooves H¹ in the ends are engaged by latches J that are carried on the outer surfaces of the mold-plates.

It is apparent that with the latches set at closed position, the mold plates will be held securely in place. The plastic concrete mixture is then deposited in the mold, completely filling same; the mold plates are presently removed and the tie bolts H are also removed. To develop the said unit further, the mold plates are disposed at a higher position as shown in Figure 3, the tie bolt being inserted through the holes E and F, and latched, and a subsequent and similar operation is performed, the corner structure being thus developed to such height as may be desired, and being provided with the holes D¹, E¹, F¹, and G¹, spaced as shown in Figure 5. By the use of the mold plates as described the corner structure may be constructed with rapidity and accuracy, there being no tendency for the mold-plates to become misaligned.

In constructing the wall bottom-course it is suggested that the user should work to a line drawn from one corner structure to the other, so that in working the wall mold-plates presently to be described, the said bottom-course will have been developed in straight form, and as it should be preparatory to the maturing and building up of the superincumbent deposits of plastic material which is to constitute the wall proper.

Each of the complementary wall mold-plates K of sheet metal, is eighteen inches high and thirty-six inches long and about three-eighths of an inch thick, and may be provided with exterior stiffener ribs K¹; when latched to the position shown in Figure 7 the faces of the inturned end portions K² are at registration, and the hinged bottom gates K³ are at vertical or closed position. The forward portions of these plates are retained at spaced distance apart

by tie bolts H, and the rearward portions of said plates are fastened by similar bolts on each side of one leg of the corner structure. Into the mold thus formed, and as shown in Figure 6, there is constructed the first section of the wall bottom-course, and designated as 1. (See Figure 9.) After the mold so constituted as described, is properly filled with the plastic material, bolts H are unlatched and removed, and the mold-plates K are set up again in a manner similar to that just described; a second section, designated as 2, of the wall bottom-course is then formed. Additional sections may be formed in the manner as just described until the wall bottom-course will have been completed, and the bolts H removed.

The superincumbent portion of the wall is formed in the manner as follows:

In the several holes, thus formed, in the upper portion of the first course, are inserted the cross pins L. Each of these pins is of the construction and function illustrated in Figure 14, being of diameter to fit easily in the hole provided by the removing of the tie bolt H, and of length to provide bearing for a track bar M that is disposed longitudinally on each side of the concrete wall section. At spaced location on the bottom of this track bar are check lugs M¹ to engage the opposite sides of the ends of the cross pins, thereby holding the track bar against longitudinal movement. On the outer vertical leg of this track bar, are loosely disposed latches, M², of form as shown in Figure 15 and spaced to register with the cross pins in the holes in the wall. The nose of this latch M² is adapted to engage an annular groove L¹ that is provided near the end of the cross pin and at such location relative to the nose of the latch that when the latches are operated the track bars are held firmly against each side of the wall structure. This track bar is angle shaped in cross section, and at spaced distances on the vertical leg (as shown in Figure 15), are clamps M³. This clamp (as shown in Figure 18) so functions that when it will have been moved to the position as shown, the mold-plate is clamped tightly against the wall.

The method of handling the mold-plates and forming the successive sections which are to constitute the superincumbent portions of the wall structure, is apparent by inspecting the views Figures 10, 11, and 12, the mold-plates being disposed on the track bars M. The use of bolts H at the upper holes only is necessary, the lower portions of the mold-plates being held by clamps M³. To remove the mold plates, the clamps M³ are thrown to the dotted line position. With the release of the lower portion of the mold plates, the tie bolt latches are easily operated thereby detaching the plates from the tie

bolts. The tie bolts are then removed, and the mold-plates are moved slidingly along the track bars to the next advanced position (see Figure 12). Tie bolts are again inserted at place and latched. Then the clamps M^3 are thrown to closed position thereby holding the plates at snug contact with the outer faces of the wall subsection. It is observed in Figure 14 that this area of contact is sufficient to provide correct vertical alignment of the mold-plates.

After the wall will have been completed, the holes may be filled from the exterior surface of the wall, the interior portions being left open for the purpose of either receiving the plastering material that may be applied, or serve as recesses in which nailing plugs or blocks may be inserted. Where walls are to be provided with ventilated interior surfacing, wooden stringers or nailing strips may be secured to the wooden plugs retained in said holes.

By means of the simple and economical construction, combination and arrangement of parts shown and described, it is possible for a person of only ordinary skill to construct the corner structures and walls, which would otherwise be not available.

It is obvious that the general principles involved in my present invention are capable of being embodied in mold plates and forms of different thicknesses, widths and heights. By providing configurated inner surfaces for the mold plates, there may be had relief effect of any desired design for the outer surface of the wall.

While sheet steel is considered suitable as the kind of metal desired for the mold plates, it is practicable to construct the mold plates of cast aluminum provided with external stiffening ribs, and the inner faces of which may be provided with variegated designs in relief, either for utility for purpose of ornamentation, or for the purpose of providing surfaces adapted especially for the receiving of stucco or other external finishing material.

What I claim as my invention, and desire to secure by Letters Patent, is:

1. An apparatus of the kind described, comprising mold plates spaced apart, tie bolts to retain said plates at position and which said tie bolts are capable of being removed from the concrete material deposited between said plates, cross pins adapted to be disposed in the holes formed by the said tie bolts, longitudinal track bars to rest on the projecting portions of the cross pins and to support a mold plate at each side of the concrete structure, latches to secure the said track bars, and clamping means to hold the mold plates against the wall structure.

2. An apparatus of the kind described, comprising complementary mold plates, tie bolts to retain said plates spaced apart, and

which tie bolts are capable of being removed from the concrete, cross pins adapted to be disposed in the holes formed by said tie bolts, a track bar at each side of the concrete structure, latches to secure the track bars on the projecting portions of the cross pins and to hold said bars against the sides of the concrete structure, means between the track bars and the mold plates to press the latter against the sides of the concrete structure.

3. Apparatus of the kind described, comprising complementary mold plates, tie bolts to retain said plates spaced apart and which are removable from the molded structure after the mold plates are removed, cross pins to be disposed in the holes formed by said tie bolts, track bars to rest on the end portions of the cross pins and to support a mold plate on each side of the molded structure, latches to connect the track bars and cross pins together, and clamps to hold the mold plates against the sides of the molded structure.

4. An apparatus of the kind described, comprising complementary mold plates having plain rearward ends, their forward ends being turned inwardly to become coengaged when the mold plates are at set position, tie bolts to hold the mold plates at spaced position apart, and which are capable of being removed from the molded structure after the mold plates are removed, cross pins adapted to be disposed in the holes formed by said tie bolts, longitudinal track bars adapted to rest on the projecting portions of said cross pins and to support a mold plate at each side of the upper portion of the molded structure, latch connections between the track bars and the said cross pins to hold the track bars at position, and means between the track bars and the mold plates to hold the latter against the sides of the molded structure.

5. An apparatus for molding, comprising matched mold plates in which to mold a corner structure, tie bolts to retain the mold plates spaced apart and which are adapted to form holes in the vertical portion of said corner structure, complementary wall mold plates having plain rearward ends and whose forward ends are inturned to coengage each other, tie bolts to fasten the rearward ends of the wall mold plates to the said corner structure, and similar tie bolts to retain the forward upper portions of the wall mold plates spaced apart, and which said tie bolts are removable from the molded structure after the mold plates are removed, substantially as and for the purposes described.

6. An apparatus of the kind described, comprising matched mold plates in which to mold a corner structure, tie bolts for said mold plates and which are located near the

edge of said plates and which are removable from the molded structure after the mold plates are removed, complementary wall mold plates whose rearward ends are adapted to 5 register on each side of one leg of the corner structure, longitudinal track bars angle shaped in cross section and upon whose horizontal legs the lower edges of the mold plates are adapted to rest, cross 10 pins in the molded structure whose projecting portions are adapted to support the

track bars, clamp devices between the track bars and the mold plates, latching means between the cross pins and the track bars to hold the latter against the sides of the 15 molded structure, and tie bolts to retain the upper portions of the wall mold plates spaced apart, and latching means carried by the mold plates whereby the plates may be connected to the tie bolts.

JAMES R. COMPTON.
